UNITED STATES PATENT OFFICE.

AUGUSTUS ABBOTT, OF NEW YORK, N. Y., ASSIGNOR TO ABBOTT COIN-COUNTER COMPANY, OF NEW YORK, N. Y., A CORPORATION OF DELAWARE.

COIN-PACKAGING DEVICE

1,025,228.

Specification of Letters Patent.

Patented May 7, 1912.

Application filed September 16, 1911. Serial No. 64,636.

To all whom it may concern:

Be it known that I, AUGUSTUS ABBOTT, a citizen of the United States, and residing at New York, in the county of New York and State of New York, have invented certain new and useful Improvements in Coin-Packaging Devices, of which the following is a specification, such as will enable those skilled in the art to which it appertains to make and use the same.

This invention relates to devices for use in forming packages of coins or placing coins in packages, and the object thereof is to provide a simple and effective device of this class which may be conveniently manipulated by hand and which is inexpensive and designed for use in connection with or on a table, desk or other support on which the coins are placed.

The invention is fully disclosed in the following specification, of which the accompanying drawing forms a part, in which the separate parts of my improvement are designated by suitable reference characters in each of the views, and in which:

Figure 1 is a perspective view showing my improved coin packaging device and showing one step in the method of its operation; Fig. 2 a perspective view of the packaging device and showing another step in the operation thereof, and Fig. 3 a partial section on the line 3—3 of Fig. 2.

In the practice of my invention I provide a tube *a* which is closed at one end as shown at *a*² and the other end of which is enlarged and flared or made slightly bell-shaped in form as shown at *a*³, and also preferably oblong in cross section, and one side thereof, the back side when in use, is cut out transversely thereof at an angle to said end as shown at *a*⁴ to form V-shaped recesses *a*⁵ at the opposite sides thereof and said end is also provided with projecting wings *a*⁶ which extend outwardly over said recesses and are also turned or directed laterally as clearly indicated in Figs. 1 and 2.

In the use of this device, the coins *b* to be placed in packages are placed on a table, desk or other support *c* and the tube *a* is grasped in one hand as shown at *d* and held at an angle of about 45 degrees to the table *c* with the edge of said table entering the recesses *a*⁵. The other hand *e*, or the fingers thereof are then used for sliding

the coins into the tube, and in this operation said coins fall into the bottom of the tube as shown at *b* in Fig. 3, and when the required number of coins have been thus deposited in the tube, a tubular package *f* of paper or other fibrous material and one end 55 of which is open, is inserted into the tube *a* as shown in Fig. 2 and the said tube is inverted, and said coins slide from the tube *a* into the tubular package *f*, as will be readily understood, after which the open end of the 60 package tube *f* is closed or folded in the usual manner.

With the construction above described it will be seen that the back of the enlarged end of the tube *a* projects above the table, 70 desk or other support *c* when the device is in use as shown at *a*⁷, and the wings *a*⁶ form, in connection with the back of the enlarged end of said tube, a guide-way or chute which leads thereto and the sliding of the coins 75 into the device may be quickly and easily effected.

This device is simple in construction and comparatively inexpensive, and by means thereof coins of any dimensions may be 80 quickly placed in packages, and it will be understood that the dimensions of the device will depend upon the dimensions of the coins to be placed in said packages.

Having fully described my invention, 85 what I claim as new and desire to secure by Letters Patent, is:

1. A device of the class described, consisting of a tube closed at one end and open at the other, the open end being slightly enlarged and one side thereof being cut away at an angle to said end and provided with projecting wing portions.

2. A device of the class described, comprising a tube open at one end and closed 95 at the other, the open end being enlarged and made oblong in cross section, and one side portion thereof being cut away at an angle to said end and provided with projecting wing portions.

In testimony that I claim the foregoing as my invention I have signed my name in presence of the subscribing witnesses this 14th day of September 1911.

AUGUSTUS ABBOTT.
